UNITED STATES PATENT OFFICE.

THOMAS CARROLL, OF DAYTON, OHIO, ASSIGNOR, BY MESNE ASSIGNMENTS, TO THE NATIONAL CASH REGISTER COMPANY, OF DAYTON, OHIO, A CORPORATION OF OHIO, (INCORPORATED IN 1906.)

CASH-REGISTER.

No. 903,837.

Specification of Letters Patent.

Patented Nov. 17, 1908.

Application filed March 23, 1904. Serial No. 206,422.

To all whom it may concern:

Be it known that I, THOMAS CARROLL, a citizen of the United States, residing at Dayton, in the county of Montgomery and State of Ohio, have invented certain new and useful Improvements in Cash-Registers, of which I declare the following to be a full, clear, and exact description.

The present invention relates more especially to the type of cash registers shown in United States Letters Patent #703,639, dated Jul. 1, 1902, and the principal object of the invention is to provide this type of machine with means for disabling at will the connections for bringing into gear the selected counter of the multiple counter series. In this particular type of machine a plurality of counters are mounted in a suitable carrier which is adjustable to bring any one of the counters into position for gearing with the differential driving mechanism, and the said carrier is mounted in a movable support whereby the selected counter may be moved into and out of mesh with said driving mechanism. This multiple counter construction is employed in addition to the grand totalizing counter and is intended for segregating the transactions according to their character or identity of clerks. The present invention has no reference to throwing out of the main or grand totalizing counter which is a common expedient, but as before stated, relates to the throwing out of the multiple counters. It will be seen at once that this pertains more especially to a multiple counter machine in which the different counters are allotted to the different clerks rather than different characters of transactions, and as it is intended to keep separate records only of the cash taken in by these clerks, it is desirable to provide for disabling the connections whereby a selected counter is brought into gear with the driving mechanism in all cases of special transactions such as those commonly known in the art by the appellations "charge" and "paid out." Although as above stated, the throwout feature of this invention is particularly applicable to a multiple counter machine in which the counters are allotted to different clerks, still it may be desirable in such a machine to provide in addition a special bank

of clerks' keys, as for example, to control special indicating, printing or multiple drawer mechanism.

The invention therefore contemplates a further improvement having for its object compelling the use of one of such clerks' keys before adjustment of the multiple counter devices.

While as stated, the counters would be allotted to different clerks, the invention is not confined to any such feature for the counters might be allotted to different departments of a business and still the throwout counter scheme would have utility.

With these and incidental objects in view, the invention may be said to consist in certain novel features of construction and combinations of elements, the essentials whereof are recited in the appended claims and a preferred form of embodiment of which is hereinafter specifically described and illustrated in detail in the accompanying drawings forming part of this specification.

Of said drawings: Figure 1 represents a side elevation of a machine of the type hereinbefore indicated having the present invention embodied therein, some parts however being omitted and the view being as much in outline as consistent with good illustration with the purpose of bringing out clearly the features having direct connection with the invention. Fig. 2 is a somewhat similar view in the nature of a section taken from front to rear of the machine. Fig. 2^a is a detail view showing in elevation some parts which are obscured behind others in Fig. 2. Fig. 3 is a sectionalized elevation of part of the machine, the view being taken on a line from front to rear of the machine but looking in the reverse direction as compared with Figs. 1 and 2. Fig. 4 is an elevation of certain gearing whereby power is transmitted from the crank handle of the machine to the interior mechanism, this view being principally for the purpose of illustrating the lock controlled by the means for selecting the counter.

It will not be necessary to enter into a detailed description of the interior construction of the machine which is of a well-known type and sufficiently explained in the prior patent already mentioned, nor indeed is it

requisite to explain at any great length the multiple counter construction.

Reference numeral 2 represents the main framework of the machine; 3 a reel or rotary carrier for a circular series of counters 4; 5 a support or frame in which said reel or carrier is journaled and which fits guides 6 on the main frame; and 7 one of a series of toothed segments which are compounded 10 with the differential mechanism of the machine so that said segments will move to correspond with the amounts set up by manipulation of the usual amount keys.

Reference numeral 8 designates a rotation shaft of the machine which protrudes through one side and carries a cam 9 co-acting with a roller 10 on the side of the frame 5 to depress the latter. In the depressed position of said support or frame 5 20 the counter carrier 3 is positioned so that no one of its counters gears with the driving mechanism and when so positioned, said carrier can be turned to adjust any one of the counters to position directly below the 25 segments 7.

The numeral 11 designates a rack which gears with a pinion on the reel as shown in said prior patent and this rack is connected by a link 12 with one arm 13 of a bell-crank 30 lever, the other arm 14 of which projects up alongside of a notched plate 15 and serves as a handle for adjusting the counters. A latch 16 is pivoted to this handle and adapted to engage with one or another of the 35 notches in the plate 15 to latch the handle in adjusted position, and this latch has a tail-piece 17 bearing upon the longer arm of a lever 18 secured to the shaft 19 and having its shorter arm underlying the shoulder 40 of a collar 20 affixed to a shaft 21, said shaft 21 (see Fig. 4) extending entirely across the machine and carrying a locking arm 22 normally projecting into an elongated notch in a disk 23 fastened to one of 45 the rotation shafts of the machine. This disk has a recess containing a spring 24 thrusting a small bolt 25 outwardly into the notch of the disk and against the end of the latching arm 22. The purpose of the connections last enumerated is to provide for 50 the unlocking of the machine by the act of unlatching the handle 14.

It will be seen that the tail 17 of the latch 16 pressing against the long arm of the lever 18 will have the effect of rocking the same and thereby tilting the collar 20 with which moves the shaft 21 and the latch arm 22. The movement is sufficient to effect a practical disengagement of said latch arm and 60 the disk 23 permitting the bolt 25 to spring across the latching arm and prevent a re-engagement between the latter and the notch until the machine has been operated.

The numeral 26 designates the operating 65 crank handle which it will be seen is geared

to the said disk 23. However, this unlocking of the machine is not permitted to take place until one of the clerks' keys 27 is depressed.

In Fig. 3 a bank of clerks' keys is shown 70 and they coöperate with a detent 28 and the latter with a spring-drawn latch plate 29, all in a well-known manner. In order to secure the result above indicated a long arm 30 is pivoted in the lower part of the main 75 frame of the machine and coupled by a slot and pin connection to the latch plate 29 so that whenever the latter moves rearwardly this arm will be carrier rearwardly.

On the shaft 19 there is secured an arm 31 80 which abuts the upper end of the arm 30 when the latter is in its normal position. Hence it will be apparent that before the shaft 19 can be rocked, the arm 30 must move rearwardly. Consequently before the 85 latch 16 can be manipulated a clerk's key must have been pushed in.

It will be seen that when the handle 14 is in any of its adjusted positions, the latch 16 on said handle cannot be released to permit 90 the adjustment of the handle without depressing a clerk's key because of the engagement of the tail-piece 17 of the pinch lever with the pivoted lever 18. This lever 18 is locked by reason of the fact that it is rigidly mounted on shaft 19 which also carries the rigid arm 31. As the arm 31 is locked by the rocking arm 30 the pinch lever 16 cannot be moved. When a clerk's key is operated and the retaining bar 29 moved rearwardly locking arm 30 is then carried out of the path of the arm 31 and the lever 16 may then be operated.

Reverting now to the means for reciprocating the sliding support 5 for the multiple 105 counters, numeral 32 designates a pin projecting from said slide and engaged by the forked end of an arm 33 affixed to a shaft 34, which shaft, on the inner side of the outer upright of the main frame of the machine, 110 carries affixed to it a downwardly curved arm 35 having a notch 36 in the lower rearward part of its outer end, as clearly shown in Fig. 2. This notch is normally occupied by a pin or stud 37 carried by a plate 38 which 115 is pivotally connected at 39 with an arm 40 loosely mounted upon the shaft 34 and coupled to a link or pitman 41 which at its upper end is forked to embrace the rotation shaft 42 of the machine and carries a roller-equipped pin 43 engaging the groove of a 120 box cam 44 affixed upon said shaft.

It will be seen that with the above described parts in their normal relation the reciprocations of the link 41 produced by a 125 rotation of the box cam 44 will have the effect of raising the sliding support 5 for the multiple counters through the rocking of the arm 33.

The plate 38, which constitutes a tappet 130

piece for acting against the arm 36 through its pin 37, is held in its normal position by a spring 45 compressed between an ear on said plate and a corresponding ear 46 on the arm

5 40. It will be readily perceived that if the plate 38 is rocked rearwardly so as to take its pin 37 out of the notch 36, the box cam 44 can no longer effect the elevation of the sliding support for the multiple counters 10 and hence in order to prevent the selected counter from being carried into gear with the segments 7 it is only necessary to provide for disablement of said plate 38.

The reference numeral 47 designates a 15 short bank of keys which will be used for denoting special transactions, the two lower keys bearing the appellations "Paid out" and "Charge" whereas the upper key is marked "Reed. on account." These keys co- 20 operate with the usual detent 48 and the latter with the usual spring-drawn latch plate 49. There is pivoted to the latter at 25 a lever whose short arm 51 is positioned normally with its end confronting a stud or pin 52 on the plate 38 so that upon the rearward movement of the latch plate 49, said plate 38 will be displaced. Hence it follows that so long as the lever last mentioned maintains its normal adjustment, the 30 pushing in of one of the special keys will result in a disabling of the connections for elevating the multiple counter support. Thus the primary object of the present invention is attained. However, as it is de- 35 sirable to add-in amounts received on account, the long arm 53 of the beforementioned lever is coupled by a slot and pin connection with the "Reed. on account" key so that when that key is pressed in the said 40 lever will be rocked and the end of its short arm 51 carried below the horizontal plane of the pin 52 from which it results that when the latch plate 49 springs rearwardly, the plate 38 will not be displaced.

45 It will now be seen that the objects primarily stated are admirably fulfilled by the construction above described. However, it is to be distinctly understood that the invention is capable of embodiment in other forms 50 and is not limited to the particular form of embodiment here chosen for purposes of illustration.

Having thus described my invention what I claim as new and desire to secure by Letters Patent is:

1. In a machine of the character described, the combination with an operating mechanism, a plurality of counters adapted to be brought separately into operative relation 60 thereto, a movable support for said counters operatively connected with the said operating mechanism, and means for setting any one of the counters for co-operation with the operating mechanism; of means for disabling the counter-support operating con-

nections at will to prevent the set counter from moving into cooperative relation with the operating mechanism.

2. In a machine of the character described, the combination with a driving mechanism differentially-operable according to the amount set up, a plurality of counters designed to separately co-operate with said mechanism, a carrier for said counters adjustable to position any one of them for co-operation with the driving mechanism, a support for said carrier movable to take the set counter into and out of cooperative relation with the driving mechanism, and connections between said support and the latter mechanism for moving it back and forth in each operation of the machine; of means for disabling said connections at will substantially as and for the purpose described.

3. In a machine of the character described, the combination with a driving mechanism differentially-operable according to the amount set up, a plurality of counters designed to separately co-operate with said mechanism, a rotary carrier for said counters adjustable to position any one of them for co-operation with the driving mechanism, a sliding support for said carrier movable to take the set counter into and out of cooperative relation with the driving mechanism, and connections between said support and the latter mechanism for moving it back and forth in each operation of the machine; of means for disabling said connections at will substantially as and for the purpose described.

4. In a machine of the character described, the combination with a driving mechanism differentially-operable according to the amount set up, a plurality of counters designed to separately co-operate with said mechanism, a carrier for said counters adjustable to position any one of them for co-operation with the driving mechanism, a support for said carrier movable to take the set counter into and out of cooperative relation with the driving mechanism, and connections between said support and the latter mechanism for moving it back and forth in each operation of the machine; of a bank of special keys, a detent and latch plate therefor, and means controlled by said latch plate for disabling the connections between the driving mechanism and the movable support.

5. In a machine of the character described, the combination with a driving mechanism differentially-operable according to the amount set up, a plurality of counters designed to separately co-operate with said mechanism, a carrier for said counters adjustable to position any one of them for co-operation with the driving mechanism, a support for said carrier movable to take the set counter into and out of cooperative re-

lation with the driving mechanism, and connections between said support and the latter mechanism for moving it back and forth in each operation of the machine; of a bank of 5 special keys, a detent and latch plate therefor, and means controlled by said latch plate for disabling the connections between the driving mechanism and the movable support, provisions existing by virtue of which 10 the disabling means themselves are disabled when a certain one of said keys is manipulated.

6. In a machine of the character described, the combination with a driving mechanism 15 differentially - operable according to the amount set up, a plurality of counters designed to separately coöperate with said mechanism, a carrier for said counters adjustable to position any one of them for 20 cooperation with the driving mechanism, a support for said carrier movable to take the set counter into and out of coöoperative relation with the driving mechanism, and connections between said support and the latter 25 mechanism for moving it back and forth in each operation of the machine, said connections comprising a cam compounded with the driving mechanism and a vibratory member coöperating with said cam and carrying a displaceable tappet device; of manipulative means for displacing said tappet device, substantially as and for the purpose 30 described.

7. In a machine of the character described, 35 the combination with a driving mechanism differentially - operable according to the amount set up, a plurality of counters designed to separately coöperate with said mechanism, a carrier for said counters adjustable to position any one of them for 40 cooperation with the driving mechanism, a support for said carrier movable to take the set counter into and out of coöoperative relation with the driving mechanism, and connections between said support and the latter 45 mechanism for moving it back and forth in each operation of the machine, said connections comprising a cam compounded with the driving mechanism and a vibratory 50 member coöperating with said cam and carrying a displaceable tappet device; of a bank of special keys and a detent and latch plate therefor, the latter having a tappet piece to operate upon the tappet device of the 55 said vibratory member, substantially as and for the purpose described.

8. In a machine of the character described, 60 the combination with a driving mechanism differentially - operable according to the amount set up, a plurality of counters designed to separately coöperate with said mechanism, a carrier for said counters adjustable to position any one of them for 65 cooperation with the driving mechanism, a support for said carrier movable to take the

set counter into and out of coöoperative relation with the driving mechanism, and connections between said support and the latter mechanism for moving it back and forth in each operation of the machine, said connections 70 comprising a cam compounded with the driving mechanism and a vibratory member coöperating with said cam and carrying a displaceable tappet device; of a bank of special keys and a detent and latch plate therefor, the latter having a displaceable 75 tappet piece to operate upon the tappet device of the said vibratory member, with provisions for displacement of said latch plate tappet by a certain one of said special 80 keys.

9. In a machine of the character described, the combination with the counters and a selecting device movable by hand to bring one or another of said counters to position for 85 receiving the registration; of a lock for said selecting device, and a bank of keys controlling said lock.

10. In a machine of the character described, the combination with the counters 90 and a selecting device movable by hand to bring one or another of said counters to position for receiving the registration; of a lock for said selecting device, a bank of clerks' keys, a detent therefor, and a latch plate 95 controlling said lock.

11. In a cash register, the combination with a differentially operable counter and means for operating the same, of means for preventing the operation of the counter, and 100 manipulative means for disabling said preventing means.

12. In a cash register, the combination with a differentially operable counter and means for operating the same, of a manipulative device which when adjusted prevents the operation of the counter, and a second manipulative device for disabling the first manipulative device whereby to permit the 105 operation of the counter irrespective of the 110 adjustment of said first manipulative device.

13. In a cash register, the combination with a plurality of counters, of a common operating mechanism therefor, means for predetermining which counter shall be operated, means for preventing the operation of the counter so predetermined, and means for disabling said preventing means whereby to permit the operation of said predetermined counter. 115

14. In a cash register, the combination with a plurality of counters and a common operating mechanism therefor, of means for bringing any desired one of said counters into operative relation to the common operating mechanism, a movable support for the counters, means for moving said support to carry the particular counter into engagement with its counter operating mechanism, means for preventing said desired counter 130

from being brought into engagement with said operating mechanism, and means for disabling the latter preventing means whereby the counter will be carried into engagement with its operating mechanism and operated thereby notwithstanding the adjustment of said preventing means.

15. In a cash register, the combination with a differentially adjustable setting element, of a series of depressible keys, means for normally locking said setting element in any of its set positions, and means controlled by said keys for unlocking said locking means to permit the movement of said element.

16. In a cash register, the combination with a differentially adjustable setting element, of a latching device mounted thereon coöperating with abutments for latching said setting element in any desired position, manipulative determining means, a lock for said latching device, and means connected with said manipulative means for controlling said lock.

25. 17. In a cash register, the combination with a differentially adjustable setting element, of a latching device mounted thereon coöperating with abutments for latching said setting element in any desired position, manipulative amount determining means, a lock for said latching device, and means connected with said manipulative means for unlocking said lock to permit said latching device to be operated and thereby permit said adjustable element to be moved.

18. In a cash register, the combination with a differentially adjustable setting element, of a latching device mounted thereon coöperating with abutments for latching said element in any desired position, of a series of depressible keys, a lock for said latching device, and means connected with said keys for controlling said lock.

19. In a cash register, the combination with a differentially adjustable setting element, of a latching device mounted thereon coöperating with abutments for latching said element in any desired position, of a series of depressible keys, a lock for said latching device, and means controlled by said keys for unlocking said lock to permit said latching device to be operated and thereby permit the adjustment of said differentially adjustable element.

55. 20. In a cash register, the combination

with a series of keys, a differentially adjustable setting element, means for normally locking said element in any of its set positions, and means for operating said lock controlled by the keys, and operated on the adjustment of any one of said keys.

21. In a cash register, the combination with an operating mechanism, a plurality of accounting devices controlled thereby, and a setting element differentially adjustable to bring any desired accounting device into operative relation with the operating mechanism; of means for normally locking the adjustable element in any set position, a series of keys, and means operated by the adjustment of any key for releasing the locking means.

22. In a cash register, the combination with an operating mechanism, of means for normally locking same, an element differentially adjustable for different transactions in the machine for releasing said locking means, means normally locking the adjustable element, and a series of keys for operating said lock.

23. In a cash register, the combination with an operating mechanism and means normally locking same, an element differentially adjustable to provide for segregation of transactions, a series of keys, and means requiring in succession adjustment of a key and movement of the adjustable element to release the locking means.

24. In a cash register, the combination with an operating mechanism and a counter, of means for producing an operative relation between said counter and operating mechanism, means for preventing the production of such relation and means for disabling the preventing means.

25. In a cash register, the combination with a plurality of accounting devices, and a common operating mechanism therefor, of means for creating an operative relation between said operating mechanism and said devices, means for precluding the creation of such operative relation and means for disabling the precluding means.

In testimony whereof I affix my signature, in the presence of two witnesses.

THOMAS CARROLL.
